GOLF GREEN REPAIR TOOL

Warren Doble, 10424 Valley Spring Lane,
North Hollywood, Calif.

Filed Apr. 20, 1961, Ser. No. 64,835

Term of patent 14 years

(Cl. D35—2)

FIG. 1.

FIG. 2.

FIG. 1 is a front elevational view of a golf green repair tool embodying my new design, the rear being substantially the same; and

FIG. 2 is an elevational view taken from one side thereof, the opposite side being essentially the same.

I claim:

The ornamental design for a golf green repair tool as shown and described.
